UNITED STATES PATENT OFFICE.

ARTHUR L. WARNER, OF ELGIN, ILLINOIS, ASSIGNOR TO CHICAGO RAILWAY SIGNAL AND SUPPLY COMPANY, OF CHICAGO, ILLINOIS, A CORPORATION OF ILLINOIS.

RAIL EXPANDER AND CONTRACTOR.

1,412,639.

Specification of Letters Patent. Patented Apr. 11, 1922.

Application filed January 26, 1920. Serial No. 354,149.

To all whom it may concern:

Be it known that I, ARTHUR L. WARNER, a citizen of the United States, residing at Elgin, in the county of Kane and State of Illinois, have invented certain new and useful Improvements in Rail Expanders and Contractors, of which the following is a specification.

This invention relates to improvements in rail expanders and contractors.

Rail expanders are ordinarily employed to separate the confronting ends of adjacent rails so that sufficient space may be provided for the interposition of the necessary insulation.

Various forms of expanders have been proposed, some employing one screw to force the rails apart and others employing one or more screws on opposite sides of the rails.

The single screw expanders heretofore proposed are open to the objection that the expanding forces are unsymmetrically or unequally applied to the rail with the result that the ends of the rails are warped or skewed out of proper alignment. The warping of the rails causes the screw to bind, and operation becomes difficult or impossible.

The multi screw expanders are objectionable because the operation of one screw causes the others to bind and, in order to attain any degree of satisfaction, the different screws must be operated simultaneously or by relatively slight equal amounts in rotation.

One of the objects of this invention is to provide an improved rail expander and contractor.

Another object is to provide a single screw expander and contractor which will exert equalized or symmetrically applied forces upon the head of the rail.

Another object is to provide a device in which the skewing action is materially reduced or entirely eliminated.

Another object is to provide a device which clamps the adjacent rails on the face and under opposite sides of the head.

Another object is to provide a device wherein the operating screw is in the vertical plane of the rail axis and close to the face of the rail head.

Another object is to provide a device which may be used readily with different sizes of rails and may be employed close to switch frogs.

Another object is to provide a device wherein the adjusting screws for clamping the jaws thereof to the rail are relieved of undue strains.

Another object is to provide a device operated by the differential action of a single screw having two sets of threads of the same direction but different pitch.

Other, further and more particular objects of my invention will become readily apparent to persons skilled in the art from a consideration of the following description when taken in conjunction with the drawings, wherein:

Fig. 1 is a perspective view of the expander device with its clamps secured to adjacent ends of two rails.

Fig. 2 is an end view of the same.

Fig. 3 is a plan of the left hand clamp and a section, just above the face of the rail, of the right hand clamp.

Fig. 4 shows the left side, or end, an elevation of one side of the clamp, while the right side shows a vertical, central section.

Fig. 5 shows a section taken on line 5—5 of Fig. 3.

In all the views the same reference characters are employed to indicate similar parts.

The device shown has a clamp 10, on one end of the screw threaded spindle 11 and a clamp 12 on the other end. The spindle 11, is provided with a thread 13 on one end, of relatively coarse pitch, and a thread 14 on the other end, with finer pitch. Both threads are in the same spiral direction, that is to say: the screw or spindle 13 bears two groups of like threads of different pitch. The clamp members 10 and 12 are substantial duplicates of each other. I have therefore indicated the several parts with reference characters differentiated only by the exponent "prime."

The clamps 10 and 12 engage the ends 15 and 16 of adjacent rails. Each clamp is provided with a saddle 17. The saddle, 17, has outwardly extending ends 18, and a centrally depressed portion 19. The portion 19, of the saddle, has in its face two corrugated, hardened steel plates 20. These plates are for contact with the tread surface or face 21 of the rail. The saddle, 17, also provides two spaced-apart shoulders 22 on each of its sides, between which are positioned two lower jaws 23 and 24. The jaws, 23 and 24, are provided with a relatively wide rib 25

for inclusion between the shoulders 22 on the saddle 17, as clearly shown in Fig. 1. The object of the ribs, 25, is to relieve the vertical screws, 26 and 27, from strain. The 5 screws, 26 and 27, pass through elongated holes 26^a and 27^a in the saddle 17 and into the jaws, 23 and 24, respectively. One of the objects of elongating the holes 26^a and 27^a is to enable the jaws to be quickly and 10 conveniently removed from the rail. To remove the clamps from the rails, one of the vertical screws 26 or 27 is loosened until the outer end 32 or 33 of the jaws drops down below the end 35 of the saddle, whereupon 15 the loosened screw and jaw may be moved until its gripping plates 28 are no longer under the head of the rail, then the device may be rotated laterally, the other jaw serving as the fulcrum, until the loosened jaw 20 is clear of the rails. This operation saves the necessity of entirely removing either of the jaws to take the device from the rails. The inner ends of these jaws are each provided with two gripping plates 28, held in 25 the respective jaw in suitable depressions by screws 29. The plates 28, are hardened and preferably corrugated and make contact with the under surface of the head of the railway rail 15. The inner and under surface 30 of the head of the rail is more or less tapered and screws 30 and 31 pass through the outer extending end 18, of the saddle 17, and engage the outer extended ends 32 and 33 of the jaws, 23 and 24, respectively. The 35 object of the screws, 30 and 31, is to maintain the inclination of the clamping surfaces of the jaws, 23 and 24, for all sizes of the rail head with which they engage. A part of the end 18 of the saddle projects downwardly, as at 35, to hold the clamping surfaces 28 up to the rail when the screws 26 and 27 are rotated for producing the clamping effect. The outer ends of jaws, 23 and 24, are elevated, so as to avoid guard rails, 40 or frog rails, which are substantially parallel with the rails to which the device is applied.

The saddle 17 is reinforced, as at 36, to provide metal for the spindle screw 11, and 50 for the screws 26 and 27. The screw 11 is placed between the vertical screws, 26 and 27, in a recess or hollow 37 just above the part 19 that is immediately above the rail. This brings the screw 11 immediately over 55 the rail and in axial vertical position therewith. The screw 11 is enlarged, in a central portion, as at 39. The enlarged part 39 is provided with holes 40 into which a bar may be inserted for rotating the screw. 60 Each clamp of the expander grips or bites the corresponding rail on the face and under opposite sides of the head. The pull or thrust, depending on the direction of rotation of operating screw 11, is therefore symmetrically applied relative to the head cross 65

section. The forces are therefore equalized and there is substantially no tendency to skew or warp the rails out of alignment. Each clamp gives the effect of a three point application of thrust or pull upon the rail 70 head cross section.

A differential action of the screw 11, is due to the differences in the thread pitch of the two threaded ends, which produces relatively small increments of movement of the 75 clamps from or toward each other with each rotary impulse imparted to the spindle, and more power with less effort than could be practically accomplished with a spindle provided with a right and left hand screw 80 thread on its respective ends, or with a spindle axially fixed at one end and provided with a very fine screw thread pitch at the other end. The latter construction would be particularly inexpedient owing to the 85 lack of strength of the relatively fine threads incident to the slight pitch thereof. In the present case the threads 13 and 14 are both relatively coarse and there is a slight difference in the pitch of the respective threads 90 which produces the desired effect and renders the screw spindle unusually powerful and strong for the purpose intended.

The rotation of the spindle requires a larger number of impulses to separate the 95 clamps a given distance but the resistance to rotation is correspondingly less than if a right hand screw thread were used on one end and a left hand thread on the other.

While one use of the device is to separate 100 adjacent rails for a definite purpose, it is clearly apparent that by rotating the spindle in an opposite direction, the ends of the rails may be made to approach each other.

Having described my invention what I 105 claim as new and desire to secure by Letters Patent is:—

1. A rail expander and contractor having a pair of clamps each with adjustable jaws, each jaw having a plurality of rail contacting surfaces for engaging the face and diametrically opposite sides of the bottom of the head of adjacent rails, and a single screw 110 cooperating with both clamps and operable to cause the clamps to approach and recede 115 from each other.

2. A rail expander and contractor having a pair of rail clamps each provided with jaws, each jaw having a plurality of rail contacting surfaces capable of exerting equalized forces upon the rail head in the direction of its length, and a single screw 120 provided with two sets of differential threads separated in the same direction and of different pitch which cooperate with the clamps 125 to cause the same to approach and recede from each other when the screw is turned.

3. A rail expander and contractor comprising a pair of clamps, each clamp having a relatively fixed upper jaw to grip the face 130

of a rail head, and two adjustable lower jaws having a plurality of rail-contacting surfaces for gripping diametrically opposite sides of the rail below the face; and a single screw having groups of like threads of different pitch cooperating with both clamps and operable to cause the same to approach and recede from each other.

4. A rail expander and contractor comprising a pair of rail clamps, each having an upper jaw for gripping the face of a rail, and a pair of independently adjustable lower jaws for gripping the rail on diametrically opposite sides below the face; and a single screw having groups of like threads of different pitch threading into both clamps and operable upon rotation to cause the clamps to approach and recede from each other.

5. A rail expander and contractor comprising a pair of rail clamps, each having an upper plural contact jaw for gripping the face of a rail, and a pair of lower plurality contact jaws for gripping opposite sides of the rail below the face; and a single screw having groups of like threads of different pitch symmetrically arranged relative to the jaws of each clamp and cooperating with

both clamps to exert equalized forces upon each rail to cause the ends of the same to approach and recede from each other.

6. A rail expander and contractor comprising a pair of rail gripping clamps, each having symmetrically arranged jaws to grip a rail between them; and a single screw having groups of like threads of different pitch positioned to lie substantially in a vertical plane passing through the axis of a rail and cooperating with both clamps to cause the same to approach and recede from each other.

7. A rail expander and contractor comprising a pair of rail clamps, each clamp having an upper jaw and two lower jaws, each jaw having a plurality of rail-contacting surfaces for symmetrically gripping the head of a rail; and a single differentially threaded screw having groups of like threads of different pitch cooperating with both clamps to cause the same to approach or recede from each other in accordance with the difference in pitch of the differential threads.

In testimony whereof I hereunto subscribe my name.

ARTHUR L. WARNER.
